[57] **CLAIM**

The ornamental design for a backing support for windscreen wiper blades, as shown and described.

DESCRIPTION

FIG. 1 is a perspective view of a backing support for windscreen wiper blades showing my new design;

FIG. 2 is an end elevational view, the opposite end being a mirror image thereof;

FIG. 3 is a side elevational view, the opposite side being a mirror image thereof;

FIG. 4 is a top plan view thereof; and

FIG. 5 is a bottom plan view thereof.

The backing support is shown broken away in FIGS. 3, 4 and 5 to indicate indeterminate length.

FIG. 2

FIG. 3

FIG. 4

FIG. 5
